(57) **CLAIM**

The ornamental design for a camera mount, as shown and described.

DESCRIPTION

1.1 is a front perspective view of a camera mount showing my new design;

1.2 is a rear perspective view thereof;

1.3 is a front elevational view thereof;

1.4 is a rear elevational view thereof;

1.5 is a left-side elevational view thereof;

1.6 is a right-side elevation view thereof;

1.7 is a top plan view thereof;

1.8 is a bottom plan view thereof;

1.9 is an explode view thereof; and,

1.10 is an enlarged view of the knob portion of figure 1.1.

The broken lines depicting all features are for the purpose of illustrating portion of the camera mount that form no part of the claimed design.

1 Claim, 10 Drawing Sheets
